FOREIGN PATENT DOCUMENTS

CN 304992470 * 1/2019

Primary Examiner — Paula Allen Greene(74) *Attorney, Agent, or Firm* — W&C IP(57) **CLAIM**

The ornamental design for a headphone, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a headphone;

FIG. 2 is a front elevational view of the headphone;

FIG. 3 is a rear elevational view of the headphone;

FIG. 4 is a top plan view of the headphone;

FIG. 5 is a bottom plan view of the headphone;

FIG. 6 is a left side elevational view of the headphone;

FIG. 7 is a right side elevational view of the headphone;

FIG. 8 is a first reference perspective view of the headphone, the only difference being the color;

FIG. 9 is a second reference perspective view of the headphone, the only difference being the color; and,

FIG. 10 is a third reference perspective view of the headphone, the only difference being the color.
